MUFFLER

George A. Kingsley, Jackson, Mich.; Ruth Riethmiller, administratrix of said George A. Kingsley, deceased, assignor to Hayes Industries, Inc., Jackson, Mich., a corporation of Michigan

Application April 5, 1935, Serial No. 14,848

12 Claims. (Cl. 181—48)

The present invention relates to improvements in noise suppression devices and more particularly to exhaust mufflers for internal combustion engines.

5 As its principal objects, the invention is directed to increasing the noise suppression in sound wave attenuating types of mufflers generally having relatively telescoping shells, the inner shell providing, at least in part, a through 10 passage for the exhaust gases. In this type of muffler, to obtain compactness, the through passage in some constructions may be broken up into sections and the gases pass longitudinally back and forth as shown in my copending application, Serial No. 14,850, filed April 5th, 1935. Mufflers of this type have the advantage that effective back pressure against the flow of the exhaust gases does not become objectionable at high engine speeds.

20 In muffler constructions of the aforesaid type, the inner shell constituting the main passage for the gases is generally in communication with embracing chambers constituting resonators or acoustic wave filters. Communication with these 25 chambers is generally effected by simple circular perforations formed in the inner shell although it has been heretofore suggested to alter the configuration of such perforations slightly to improve the degree of noise suppression as disclosed 30 in the patent to Oldberg, No. 1,938,973.

It has been found that perforations heretofore provided in the inner shell of the aforesaid type of muffler results in the creation of objectionable high pitched or "whistling" noises and it is the 35 primary object of the present invention to provide perforations which will eliminate entirely or at least greatly diminish such noises. A further object is to provide perforations which not only will eliminate "whistling" but which at the 40 same time will impart a whirling action to the gases passing through the inner shell increasing the degree of noise suppression as compared with similar muffler structures differing only in the configuration of the perforations in the inner 45 shell.

Other objections and advantages of this invention reside in the details of construction and arrangement of parts to be more fully developed by the following description and accompanying 50 drawing, in which

Fig. 1 is a broken sectional view of a muffler embodying the features of the invention,

Fig. 2 is a cross sectional view taken on the line II—II of Fig. 1, and

55 Figs. 3 to 7, inclusive, are fragmental cross sec-

tional views of modified perforation structures.

In general the present invention comprises a muffler structure of the aforesaid type having a perforated inner shell embraced by longitudinally spaced chambers. Elongated slots in lieu 5 of conventional circular perforations are provided in the inner shell. These slots are preferably angularly disposed with reference to the longitudinal axis of the shell. Also the configuration and position of these slots is such that the 10 flow of gas breaks over sharp or pointed corners at the leading ends of the slots and preferably over similar corners at the trailing ends of the slots. It has been found that slots of such a character obviate "whistling" noises heretofore 15 created by the passage of the exhaust gases in such muffler constructions. Also it is the present theory that the angularly disposed slots impart a whirling action to the gases passing through the inner shell, accounting for the increase in 20 noise suppression.

Referring specifically to the drawing, the muffler structure 10, chosen to illustrate the principles of the invention, comprises an outer shell 12, an intermediate shell 14 and an inner shell 16. In this type of structure the inner shell 16 25 constitutes a straight through passage for the exhaust gases; the outer and inner shells define chambers constituting acoustic wave filters or resonators. Baffles 18 and 20 concentrically position the shells 14 and 16 within the outer shell 12; the baffles 18 form chambers 22 between the shells 12 and 14 while the baffles 20 form chambers 24 between the shells 14 and 16. Generally there is no communication between the chambers 22 and 24 through the baffles 18 and 20, although 30 in some constructions it may be found desirable to perforate either the baffles 18 or the baffles 20, or all of them.

Referring to Fig. 1 the inner shell 16 is provided with a plurality of angularly disposed elongated perforations 26 opening into the longitudinally spaced chambers 24. As shown, the perforations 26 are in the form of elongated slots having a pair of opposed sides 28—30 angularly disposed with reference to the axis of the shell 16 and opposed sides 32—34 parallel to the axis of the shell 16. This results in providing a sharp corner for the gas to break over at the leading and trailing ends of the perforations. This would be equally true if the sides 32—34 were normal to the sides 28—30 or slightly curvilinear to facilitate the punching operation. It is to be understood that the angularity, width and length of 40 perforations and longitudinal grouping and posi- 45

5. A muffler of the type described comprising an outer shell having inlet and outlet openings, an inner shell through which the gases are directed, a chamber defined between said shells 5 constituting an acoustic wave filter or resonator, and elongated perforations defined in said inner shell communicating with said chamber and the interior of said inner shell, said perforations presenting sharp corners at the leading ends 10 thereof and their sides throughout their entire length being non-perpendicular to the flow of the gases.
6. A muffler of the type described comprising an outer shell having inlet and outlet openings, 15 an inner shell through which the gases are directed, a chamber defined between said shells constituting an acoustic wave filter or resonator, and elongated perforations defined in said inner shell communicating with said chamber and the 20 interior of said inner shell, said perforations presenting sharp corners at the leading and trailing ends thereof and their sides throughout their entire length being non-perpendicular to the flow of the gases.
- 25 7. A muffler of the type described comprising means defining a passageway through which the exhaust gases are directed, elongated slots defined in said means to effect communication with an area of said structure embracing at least a portion of said means, said slots being angularly disposed throughout their lengths and having their sides non-perpendicular to the general direction of the flow of gas through said passageway.
- 30 8. A muffler of the type described comprising means defining a chamber into which the exhaust gases are directed, elongated slots defined in said means to effect communication with an area of said structure embracing at least a portion of 35 said means, said slots being angularly disposed throughout their lengths and having their sides non-perpendicular to the general direction of the flow of gases into said chamber.
9. A muffler of the type described comprising means defining a chamber into which the exhaust gases are directed, elongated slots defined in the general surface of said means to effect communication with an area of said structure embracing at least a portion of said means, said slots having certain opposed sides thereof angularly disposed to the general direction of the flow of gases into said chamber and certain other sides parallel to the flow. 10
10. A muffler of the type described comprising means defining a chamber into which the exhaust gases are directed, elongated slots defined in said means to effect communication with an area of said structure embracing at least a portion of 15 said means, all the sides of said slots being non-perpendicular to the general direction of the flow of gases into said chamber.
11. A muffler of the type described comprising an outer shell having inlet and outlet openings 20 for exhaust gases, an intermediate shell, and an inner shell constituting a passageway between said openings, baffles dividing the space between said shells into chambers, and means providing communication between the chambers defined by 25 said intermediate shell with said outer shell and said inner shell, said means including elongated slots defined in said inner shell.
12. A muffler of the type described comprising an outer shell having inlet and outlet openings 30 for exhaust gases, an intermediate shell, and an inner shell constituting a passageway between said openings, baffles dividing the space between said shells into chambers, and means providing communication between the chambers defined by 35 said intermediate shell with said outer shell and said inner shell, said means including elongated slots angularly disposed with reference to the general direction of the flow of gases through said inner shell. 40

DISCLAIMER

2,088,296.—*George A. Kingsley*, Jackson, Mich. MUFFLER. Patent dated July 27, 1937. Disclaimer filed August 31, 1939, by the assignee, *Hayes Industries, Inc.*

Hereby enters this disclaimer, to wit: It is hereby disclaimed from the scope of claims 4, 5, 6, and 10 any and all muffler construction except those in which the perforations in the inner shell are disposed in the major curvilinear surface of the inner shell by which they are defined; so-called louver type of perforations formed by deflecting portions of the inner shell radially outward, being specifically disclaimed.
